THERMOSTAT WITH FRICTIONAL SNAP ACTION

Robert Valverde, New York, N. Y.

Application May 1, 1947, Serial No. 745,163

8 Claims. (Cl. 200—138)

1

This invention relates to an improvement in a thermostat with frictional snap action using the principle that static friction is greater than moving friction. I have discovered that in applying friction between the moving contact and the fixed contact of a creep type thermostat the members of the friction couple must, in the direction of motion of the moving contact, be substantially immovable or fixed with respect to their respective contacts. That is, the friction member attached, directly or indirectly, to the moving contact must have no motion with respect to the moving contact in the direction of motion of the moving contact. Likewise, the friction member attached, directly or indirectly, to the fixed contact must have no motion with respect to the fixed contact in the direction of motion of the moving contact. The result is that no motion occurs between the contacts without motion between the friction couple.

In order that there shall be bearing pressure between the friction couple, elasticity is provided by one or both members of the couple but not in the direction of motion of the moving contact. There are several forms of friction couples in my invention with the common feature that in the direction of motion of the moving contact both are substantially fixed to their respective contacts. One form of my invention uses bimetal for the moving element or thermal motor which I will use to describe my application of static and moving friction. This bimetal normally moves directly in proportion to the change in ambient temperature. In thermal control the motion is normally microscopic. The separation and joining of contacts is accompanied with destructive sparking and any mechanical vibration makes it worse. The contacts weld to cause overheating and they wear out by evaporation to cause loss of setting.

In my thermostat with increase of temperature the contacts cannot separate until the flexible bimetal has built up a warping force greater than the static force of the friction couple. Then the contacts separate suddenly and relatively widely. They continue to separate until the diminishing warping force is exceeded by the force of moving friction, when they would normally come to rest. But if due to the current load a spark occurs, there may be backlash of the moving contact which may cause momentary closure and further destructive sparking. To compensate for the explosive force of the spark, I provide means to increase the moving friction force to bring the contact to rest without backlash.

2

Figure 1 shows a simple form of my friction thermostat with temperature adjustment.

Figure 2 is a detail view of the friction couple used in Figure 1.

Figure 3 shows a modified form of my thermostat with an L-shaped bimetal element.

Figure 4A shows another modified form of my thermostat with side friction and using the edge-on elasticity of the bimetal for friction.

10 Fig. 4B is an end view of the structure illustrated in Figure 4A, without the terminals and showing the friction couple and adjustment.

Fig. 5A is a plan view of a modified construction of the movable contact.

15 Fig. 5B is an end view of the structure shown in Fig. 5A.

Fig. 6 shows an application to a crystal oven of two thermostats of the type shown in Fig. 1.

Fig. 7 shows still another modified form of the 20 invention.

In Figure 1 on an insulated base 1 is mounted a support 2 with a bimetal strip 3 attached. A contact 4 carried by the bimetal strip touches a fixed contact 5 which screws into a bracket 6 mounted on the base 1. Terminals 7 and 8 connect to a thermal control circuit of a heater 9 and current terminal 10. Fixed into the base 1 is a friction wire 11 which presses against the tip 12 at the free end of the bimetal to form a friction couple. The friction wire 11 is at an acute angle to the bimetal strip 3 so that moving friction pressure increases and compensates for the explosive force of sparking as the contacts 4 and 5 open. This friction couple is shown in 30 Figure 2 in solid lines for the contacts-closed position of friction wire 11 and friction tip 12, and in dotted lines after the contacts 4 and 5 open. The elastic wire 11 is pushed into its dotted line position to increase the frictional pressure 35 as the bimetal 3 moves into its dotted line position. This and similar friction couples produce a true snap action without backlash. On closure the static friction again builds up potential energy in the bimetal until snap action motion 40 occurs with a diminishing moving friction to oppose a possible explosive spark and for a firm contacting.

45 Fig. 3 shows another way of causing the friction pressure to increase as the contacts open. The L-shaped bimetal element 13 has two functions; the horizontal part opens the contacts 14 and 15; the vertical part increases the frictional pressure between a friction wire 16 and a friction plate 17. The wire 16 is fixed to the bimetal tip 18 to which is fixed the moving contact 14.

50 55

The friction plate 17 is an insulator and fixed to an arm 19 which is fixed to the contact 15. Again this friction couple is unyielding in the direction of motion of the moving contact 14 so that no motion occurs between the friction couple unless the contacts separate. A pressure adjustment for the friction couple is made with a screw 20 that threads through the arm 19 and into contact with a bracket 23 of the thermostat assembly. By joining the bimetal element supporting bracket 22 to the contact bracket 23 with insulating cement 24 the thermostat is fixed to only one terminal 25 and the circuit is completed to a second terminal 26 by a pigtail 27.

Another friction couple, Figs. 4a and 4b, is obtained by the edge-on pressure of a bimetal element 30 against an adjustable finger 31, a part of a bracket 32. The free end of the bimetal 30 is formed into a shoe 29 which presses against insulation enamel 28 on the finger 31. This finger 31 is adjusted to slope outward so that the edge-on friction pressure increases as the contacts 33 and 34 open. Again there is no friction couple motion in the direction of motion of the moving contact unless the contacts separate or close.

I have discovered that the current capacity of my thermostat is increased by thermally and electrically insulating the moving contact from its bimetal. In Figs. 5a and 5b there is shown a contact of bimetal assembly which produces an extended path through the contact to permit contacting-heat to dissipate. A silver strap contact 35 is attached to a bimetal strip 36 with a thermal and electric insulating cement 37 and the contact and bimetal are joined electrically with a connector 38 at the greatest distance from the contact point. The connector 38 may extend directly to the contact terminal without touching the bimetal. In the crystal oven application shown in Fig. 6, a bimetal strip 39 is mounted in a narrow section of square plastic tubing 40 with its contact 41 touching an adjustable contact 42 which is connected to a terminal 43. This bimetal thermostat connects at terminal 44 to a heater coil 45 molded into the plastic tubing 40. A friction spring 46, pressure adjusted by a screw 47, makes a friction couple with the bimetal tip 48 in the same manner as in Fig. 1. Similarly a terminal 49, bimetal strip 50, contacts 51 and 52, and terminal 53 form a thermostat to control another heater wire 54 molded into plastic tubing 40. A front and back panel, not shown, make an oven of the plastic tubing 40 which holds an electronic crystal 55 with terminals 56 and 57. In operation the bimetal strip 39 controls a booster heater and the bimetal strip 50 controls the heater 54 to keep the crystal at a constant temperature. In Fig. 7 a bimetal strip with upper and lower portions 58 and 59, and with an adjustable contact 60 and an insulated contact 61, is mounted on a terminal post 62. One part of the friction couple is a leaf spring 63 attached to the end of the lower portion of the bimetal strip 59 with its polished surface in contact with an enamel tipped end 64 of an adjustable friction screw 65, the other part of the friction couple.

The contact screw 60 and the friction screw 65 are mounted without play in a looped end 66 of the upper portion of the bimetal strip 58. Any motion between the upper and lower portions 58 and 59 of the bimetal strip under the influence of heat causes an equal motion be-

tween the two parts 63 and 64 of the friction couple and an equal motion between the two parts 60 and 61 of the electrical contact. This motion in either direction is a snap action. A pigtail 67 connects insulated contact 61 and a terminal 68 to complete the circuit.

The preferred embodiments of the invention have been illustrated and described but changes and modifications can be made and some features of the invention can be used in different combinations without departing from the invention as defined in the claims.

I claim as my invention:

1. A thermostat including contacts, one of which is movable with respect to the other, a thermal motor connected with the movable contact, two friction elements, including a first element which is connected with the movable contact and fixed with respect to the movable contact in at least the direction of movement of said movable contact, and a second element which is relatively fixed in the direction of movement of the movable contact, a friction surface on one of said elements and with which 20 the other friction element contacts, said friction surface of one element extending at an acute angle to the direction of movement of an adjacent portion of the other element so as to change the pressure between the surfaces progressively as one friction surface moves along the other.

2. A thermostat comprising two bimetal strips supported at corresponding ends and disposed so as to warp in opposite directions with change in temperature, contacts carried by the respective strips in position to move toward and from one another as the strips warp, and friction elements carried by the strips and resisting movement of the strips with change of temperature, each of 30 said friction elements being immovable, with respect to the strip that carries it, in at least the direction of movement of the strip that carries it.

3. A thermostat comprising a substantially V-shaped bimetal thermal motor, a fixed support 45 for the thermal motor, a contact carried by one leg of the V-shaped bimetal, electrical insulation between said contact and the bimetal, a contact carried by the other leg of the V-shaped bimetal and adjustable toward and from the insulated contact to change the temperature at which the contacts come together and at which they separate, a friction element comprising a strip attached to one of the legs of the V-shape bimetal and extending across and beyond the other leg of said bimetal, and an adjustable screw on said other leg in position to slide along the friction element as the contacts move toward and from one another.

4. A creep type thermostat, as described in claim 1, and in which one of the friction elements is connected with the thermal motor and is deflectable with respect to the other friction element but non-deflectable with respect to the thermal motor in the direction in which the thermal motor moves the friction element.

5. A creep type thermostat, as described in claim 1, and in which the fixed contact is attached to a switch frame and the movable contact is fixed to the thermal motor, the frame being electrically insulated from the motor and one of the friction elements being fixed to the portion of the thermal motor that is connected with the movable contact and being resiliently pressed against an electrically insulated part of the frame but non-deflectable with respect to the moving

contact in the direction of motion of the moving contact.

6. A thermostat as described in claim 1, and in which the thermal motor comprises a part of bimetal strip having a portion which is relatively fixed and a portion which is movable, one contact comprising an element that extends around at least a part of both upper and lower surfaces of the movable portion of the bimetal strip, a layer of electrical and thermal insulating material between the bimetal and the contact element that extends around the bimetal, the other contact being fixed in position to be touched by a surface of said contact element on one side of the bimetal strip when the bimetal warps in one direction, and a flexible conductor connected with a portion of the contact element on the other side of the bimetal for establishing a circuit to a terminal of the thermostat.

7. A thermostat including contacts, one of which is movable with respect to the other, a thermal motor connected with the movable contact, two friction elements including a first element which is connected with the movable contact and movable therewith, a second element which is connected with the other contact, a friction surface on one of said elements and with which the other friction element contacts, one of the friction elements having a resilient structure that holds said friction elements in contact with

one another, the entire length of said resilient structure extending at an acute angle to the direction of movement of an adjacent portion of said other friction element.

8. A thermostat as described in claim 1 and in which the first friction element has a fixed end and a movable end, and said first friction element is shaped to provide resilience for shifting the free end across as well as along the path along which the free end of said first element is urged by the thermal motor, and the friction surface is on a member opposing movement of the free end of said first element and against which said free end is held by the resilience of said first element.
